UNITED STATES PATENT OFFICE.

ERNEST LOUIS RANKIN, OF EAST SHEEN, ENGLAND.

BRAIDING-MACHINE.

1,189,483.

Specification of Letters Patent.

Patented July 4, 1916.

Application filed August 25, 1913. Serial No. 786,492.

To all whom it may concern:

Be it known that I, ERNEST LOUIS RANKIN, a subject of the King of Great Britain and Ireland, residing at 17 Portsman avenue, 5 East Sheen, Surrey, England, have invented certain new and useful Improvements in Braiding-Machines, of which the following is a specification.

This invention for improvements in braiding machines relates to machines in which the upper and lower sets of bobbins are rotated in opposite directions by upper and lower spiders and in which the threads from the lower set of bobbins are passed under 10 and over the threads of the upper set of bobbins by means of thread throwing arms coöperating with thread passing devices the upper bobbins being mounted to slide on the periphery of the lower spider.

20 My invention has for its object to provide improved thread passing means and generally to simplify the construction of machines of this type.

According to my invention the upper bobbin carriers which are mounted on the upturned edge of the lower spider are coupled to the upper spider so as to be carried around therewith, by means of gapped disks which are mounted to rotate about vertical 30 pivots on the upper spider, and coöperate with thread throwing arms which are mounted to oscillate on oblique spindles and also with slots in the lower spider to pass the threads from the lower bobbins under and 35 over the upper bobbins. The thread throwing arms are actuated by a plate or frame which is reciprocated vertically and acts on the arms through ball crank spindles.

40 My invention also comprises other novel features hereinafter described with reference to the accompanying drawings in which:

Figures 1 and 1^a represent a sectional elevation of a braiding machine constructed according to the present invention and Fig. 2 45 is a plan of the same. Fig. 3 represents an enlarged detail sectional view illustrating the depending brackets; Fig. 4 is a detail front elevation illustrating the eccentrics. Fig. 5 is a similar view of the lower bobbins 50 with the throw over mechanism. Fig. 6 is a sectional elevation showing a modified construction of gear for operating the rising and falling plate.

As seen in Figs. 1, 1^a and 2 the machine 55 comprises a pair of spiders *a* *b* mounted coaxially on a central shaft *a'* and a hollow

shaft *b'* respectively. These spiders are rotated in opposite directions by the bevel wheels *a²* *b²* which engage the bevel pinion *c* on the driving shaft *c'*. The upper spider *a* is substantially flat while the other spider *b* is provided with an upturned edge which is gapped to allow of the passing of the threads from the lower bobbins under those from the upper bobbins.

60 In the machine illustrated eight upper and eight lower bobbins are provided.

The upper bobbin carriers *d* and their bobbins *d'* are mounted to slide on the periphery of the lower spider *b* and are carried 70 around with the upper spider *a* by the flanged disks *e* rotatively mounted thereon. These disks *e* are provided with two recesses as shown and carry pinions *e'* at their lower ends which engage intermediate pinions *e²* 75 rotatively mounted in the spider *a* and meshing with a toothed flange *b³* formed on the upper face of the lower spider *b*. The diameter of the pinion *e'* on the flanged disks *e* is a quarter of that of the toothed flange *b³* 80 in order that necessary relative motion between the flanged disks *e* and the lower bobbins may be imparted to effect the passing under the thread as hereinafter described.

The lower bobbin carriers *g* are supported 85 on brackets *g'* depending from the lower spider *b*. The thread passing mechanism which is also mounted on the lower bobbin carriers comprises a double arm lever *h* *h'* mounted on an oblique spindle *h²* passing 90 through the carrier *g*. One end *h* of the double arm lever serves for passing the thread while the other end *h'* which is forked and curved engages the ball crank *i*, the spindle *i'* of which is rotatably mounted in the bobbin carrier *g*. This spindle is also cranked at its other end and is fitted with a small roller or die *i²* which engages 95 the annular groove in the rising and falling operating plate *j*. The vertical movement 100 of the operating plate *j* is transmitted by the ball crank *i* to the thread passing arms, so that the thread from the lower bobbins is alternately raised and lowered sufficiently to pass over and under the upper bobbins. 105

It is necessary in such machines that when a defect is formed in the product that the machines should be turned backward and the defect cured by unplaiting the braid. To effect this, means for taking up the slack 110 in the thread must be provided and this is accomplished as follows:—On the bottom

spider is fulcrumed a number of arms g^2 which while the bottom spider is rotating are held out by centrifugal force and do not come in contact with the thread but when 5 the machine is stopped the arms then fall and rest on the threads so that when the machine is turned backward the weight of the arms take up the slack which is given by the unbraiding of the braid.

10 The threads from the lower bobbins g^3 are passed under the arm g^2 on the adjacent bobbin carrier and thence through the tension device h^3 arranged on the end of the spindle h^2 to the eye of the thread passing 15 arm h .

The rising and falling plate j is operated by a pair of eccentrics k mounted on two countershafts k^1 arranged on either side of and driven by spur wheels from the main 20 driving shaft c^1 . The eccentric straps are connected to the plate j by connecting rods k^2 pivoted between pairs of lugs provided on a ring j^1 slidably arranged around the boss of the plate j . The effect of this mechanism is that as the rising and falling plate j reaches the top or bottom of its stroke, the roller or dies engaged with the groove imparts less motion to the ball crank spindle, and as the ball crank spindle is partially 25 rotated in the fork of the drawing arm, the ball slides without imparting motion to the throwing arm, thereby giving a positive dwell while the thread is passing over or under the upper bobbins.

30 35 The modified arrangement of gear for operating the lower bobbins illustrated in Fig. 6 is intended to operate the thread passing mechanism in two sets, so that when one set passes the threads over the upper bobbin 40 the other set passes the threads under the upper bobbins. One set of ball cranks is operated from the rising and falling plate j actuated as described above while the other set is operated from a second plate mounted 45 on a sleeve j^2 capable of sliding on the hollow shaft b^1 . This sleeve j^2 is operated by a pair of connecting rods j^3 j^4 engaging eccentrics k^8 k^4 mounted on a counter shaft k^5 and the main driving shaft c^1 of the machine respectively. The countershaft k^5 is 50 driven by a bevel pinion k^6 meshing between the bevel wheels a^2 b^2 . By this means one

set of thread passing arms is raised while the other set is lowered and vice versa.

What I claim and desire to secure by Letters Patent is:—

1. The combination with a bobbin support; of an obliquely mounted spindle carried thereby, a double armed throwing lever mounted on said spindle, one arm of which is provided with thread receiving means and the other forked and curved, a ball crank engaged with said forked arm and having its spindle rotatably mounted in said support, a crank on said spindle, and a vertically movable member having an annular groove to receive said last mentioned crank. 60

2. The combination with a bobbin support; of an obliquely mounted spindle carried thereby, a double armed throwing lever mounted on said spindle, one arm of which is provided with thread receiving means and the other forked and curved, a ball crank engaged with said forked arm and having its spindle rotatably mounted in said support, a crank on said spindle, a vertically movable member having an annular groove to receive said last mentioned crank, and means for imparting a positive dwell to the throwing lever while the thread is passing 70 75 the bobbin.

3. The combination with a bobbin support; of an obliquely mounted spindle carried thereby, a double armed throwing lever mounted on said spindle, one arm of which is provided with thread receiving means and the other forked and curved, a ball crank engaged with said forked arm and having its spindle rotatably mounted in said support, a crank on said spindle, a vertically movable member having an annular groove to receive said last mentioned crank, and means for partially rotating said ball crank spindle in the fork of said throwing arm to cause the ball to slide without imparting motion to the throwing lever, thereby imparting a positive dwell to the throwing lever while the thread is passing the bobbin. 80 85 90 95

In testimony whereof I affix my signature in presence of two witnesses.

ERNEST LOUIS RANKIN.
